UNITED STATES PATENT OFFICE

WILLIAM A. WORTHINGTON, OF DALLAS, TEXAS.

SHADE-HANGER.

SPECIFICATION forming part of Letters Patent No. 787,252, dated April 11, 1905.

Application filed November 1, 1904. Serial No. 230,963.

to all whom it may concern:

Be it known that I, WILLIAM A. WORTHINGTON, a citizen of the United States, residing at Dallas, in the county of Dallas and State of Texas, have invented new and useful Improvements in Shade-Hangers, of which the following is a specification.

My invention relates to adjustable shade-hangers; and its primary object is to provide a novel device of this character by means of which a shade may be elevated or lowered to my desired position and retained in its adjusted position and one which is simple in construction, cheap to manufacture, durable, and efficient.

A further object of the invention is to provide an adjustable shade-hanger which may be easily secured in applied position and which is so constructed and has its parts so arranged as not to be liable to become broken or inoperative.

With the above and other objects in view the invention consists in the construction, combination, and arrangement of parts hereinafter fully described, claimed, and illustrated in the accompanying drawings, which disclose the preferred form of my invention, and in which—

Figure 1 is a plan view of the upper portion of a window-frame, illustrating the application of my improved shade-hanger. Fig. 2 is a vertical transverse sectional view thereof. Fig. 3 is a detail plan view of the bracket which is adapted to receive the pintle of the shade-roller. Fig. 4 is a similar view of a bracket adapted to receive the squared end of the shaft of the shade-roller. Fig. 5 is a detail perspective view of the rope-clamp adapted to receive the free ends of the adjusting-cords. Fig. 6 is a detail perspective view of one of the brackets.

Referring to the drawings by reference-numerals, 1 designates a window-frame, 2 a shade, and 3 a shade-roller, all being of the usual form and construction.

4 and 5 designate guide-rods, circular in cross-section and having their extremities twisted to provide eyes 5, through which fastening means are adapted to extend to secure the guide-ropes in applied position. The rods

also have their ends bent, as at 6, to space them from the window-frame to permit of brackets being slidably mounted upon said rods. The fastening means, adapted to extend through the eyes in the upper ends of 55 the guide-ropes, are provided with enlarged eyes 7 for a purpose to be hereinafter explained. The brackets are each constructed from a single strand of wire, and the strand from which the bracket disclosed in Fig. 3 is 60 made has its lower end bent backwardly and upwardly in parallel relation to the body portion and thence toward said body portion to provide a closed bearing 8 and a body portion 9, the extremity of said bent portion being 65 disposed rearwardly and horizontally and having its ends curled about one of the guide-rods. The upper end of said body portion is bent backwardly and downwardly in parallel and close relation to the body portion, and 70 the extremity of said bent portion is also disposed rearwardly and horizontally and twisted about the guide-rod. The bending of the upper end of the body portion 9 provides a space 75 10, wherein portions of the adjusting-cords are frictionally held between the parallel portions of the body 9. The strand of wire from which the bracket disclosed in Fig. 4 is constructed is similarly bent, except that the lower end of the body portion 9 is bent to provide 80 a rectangular opening 10. The pintle 11 of the shade-roller 3 is journaled in the bearing 9, and the squared end 12 of the shaft of the shade-roller is mounted in the opening 10, whereby said shade-roller is mounted in applied position. It will be perceived that as the brackets are so constructed as to close the bearing 9 and opening 10 all liability of the shade-roller becoming accidentally disengaged 85 is obviated, and it is also apparent that the twisting of the extremities of the brackets about the guide-rods hingedly secures and mounts the brackets upon the guide-rods for vertical movement. When it is desired to insert the shade-roller in applied position, the 90 pintle 11 is first swung around so as to cause the squared portion 12 of the shaft to engage in the opening 10.

An adjusting-cord 14 has one of its ends 100 passed through one of the eyes 7, then through

the spaces 10, and thence through the other eye of the free ends of said cord, depending to position its lower ends in easy reach. Said cord by reason of its frictional engagement with 5 the brackets will prevent said brackets from turning upon the guide-rods. It is apparent that the brackets may be adjusted vertically upon the guide-rods to support the shade at any desired point, and after the shade has 10 been moved to its proper position the free ends of the adjusting-cords are secured in a rope-clamp 15 to retain the shade in its adjusted position. The cord-clamp, like the brackets, is also constructed from a single 15 strand of wire, which is bent upon itself to provide an eye 16 and then at right angles and downwardly in opposite direction to provide attaching members 18. The free ends of the adjusting-cords are adapted to be inserted 20 into the eye 16 and held therein by frictional engagement, whereby the shade may be supported in its adjusted position.

Having thus fully described the invention, what is claimed as new is—

25 In an adjustable shade-roller support, a window-frame, guide-rods secured to said window-

frame, brackets slidably mounted upon said rods and constructed from single strands of wire having their lower ends bent backwardly and upwardly in parallel relation to the main or body portions thereof, and thence inwardly toward the body portions, the extremities of said bent portions being disposed rearwardly in a horizontal plane and coiled to receive the guide-rods, the upper ends of said body portions being bent rearwardly and downwardly, and thence rearwardly in a horizontal plane and twisted to receive the guide-rods, the bending of the lower portions of said wires providing a closed bearing and rectangular opening, a shade-roller having its pintle journaled in said bearing and the squared end of its shaft mounted in said opening, and an adjusting-cord secured between the upper bent portions of the brackets and frictionally held therein.

In testimony whereof I affix my signature in presence of two witnesses.

WILLIAM A. WORTHINGTON.
